CRACKING PROCESS

Harold Sydnor, Westfield, N. J., assignor to Standard Oil Development Company, a corporation of Delaware

Application July 23, 1932, Serial No. 624,256

1 Claim. (Cl. 196—51)

This invention relates to an improved cracking process in which the fresh feed is introduced into a separator held under the pressure of the soaking drum. The invention will be fully understood from the following description when read in conjunction with the drawing the sole figure of which is a diagrammatic side elevation, partly in section, of the apparatus used for carrying out the invention.

10 The efforts of the petroleum refining art have lately been directed to the production of good knock rating gasoline. This purpose can be achieved in the so-called tube and tank cracking process in which the oil to be cracked is passed through heating coils into a so-called digesting or soaking drum and the cracked product is then separated into its constituents such as tar, cycle stock, naphtha and gas. When it is required to produce a good knock rating gasoline in such a process it is necessary to maintain a higher cracking temperature than was formerly usual. A serious limitation to such high temperature tube and tank processes at the present time is the tendency of the release lines and 15 valves immediately adjacent to the drum to clog due to the accumulation of coke which terminates the run sooner than would otherwise be necessary. I have found that this coking difficulty can be eliminated by transferring the cracked material from the soaking drum into a separator held substantially under the same pressure as the soaking drum and by introducing fresh feed into the separator to cool down its contents and check the further cracking. By thus 20 maintaining full soaker pressure on the products leaving the soaking drum until they are cooled by direct contact with the incoming fresh feed, the coking of the lines adjacent to the soaking drum becomes eliminated.

25 Among the several other objects and advantages of the present invention the following are mentioned.

30 1. A higher than the usual preheat of the oil entering the heating tubes is obtained since the necessity of recirculating cold tar to the bottom of the separator for cooling becomes eliminated and the excess heat content of the cracked effluent from the soaking drum is used for preheating the fresh feed. The advantage of carrying out the direct contact of the incoming feed with the cracked products before release of pressure becomes greater as the coil outlet temperature is increased since the amount of heat to be dissipated between the soaking drum and the 35 separator of a unit operating with a low pressure

separator increases with the cracking temperature. High preheat is essential to the development of a high temperature, high pressure cracking, since it means less heating surface to reach the cracking temperature at a given feed rate, which in turn means less tubes and less pressure drop through the heating tubes.

2. It is well known that naphthas produced by high temperature cracking are unstable and contain a high percentage of gum forming constituents which have to be removed by acid treatment. It has been applicant's experience that the stability of the produced naphtha against gum formation increases when the high pressure separator of the present invention is used. Due to increased stability of the gasoline, the treatment of the same with sulfuric acid for the removal of gum forming constituents may be eliminated and the gasoline finished by simple clay treatment as will be described hereinafter.

3. I also found that the use of the high pressure separator in a cracking process results in the formation of a gasoline having greater resistance to detonation with increasing engine jacket temperature when used as a motor fuel. The resistance to detonation is a function of the chemical constitution of the gasoline and is expressed in octane numbers as well known in the art. The octane number varies with the conditions under which the engine is run and more specifically with the engine jacket temperature, there being a drop in the octane number as this temperature increases. I found that the drop in the octane number with increasing engine jacket temperature will be less when the gasoline is prepared by a cracking process using a high pressure separator according to the present invention.

4. In one modification of the present process the fresh feed is introduced at the top of the separator while the cracked product is introduced at or near the bottom of the same so that the hot vapors and the cooler liquid pass in countercurrent to each other. It will be seen that a clean and fresh distillate feed stock is thus obtained for the passage through the heating tubes of the furnace and any difficulty due to deposition of coke in the heating tubes on account of unclean charging stock is eliminated.

Referring now to the drawing the same will be described in conjunction with the method of operating the process. The feed stock consisting of fresh feed distillate and cycle stock is pumped from accumulator 1 through line 2 and preheater 3 to the heating coil 4 arranged in furnace 5. The oil is heated in the coil to a cracking temper-

ture and then discharged into the digester or soaking drum 6 in which the desired degree of cracking takes place. The hot cracked effluent leaving the drum by line 7 is then transferred into the high pressure separator 8 in which it is cooled by partially preheated fresh feed in order to check the further progress of the cracking and to simultaneously vaporize the vaporizable constituents of the latter. Fresh feed from tank 9 is pumped through heat exchange coil 10, heat exchanger 11 and line 12 to the top plate of the separator 8. Valve 13 and line 14 allow the passage of a small part of the preheated fresh feed to the bottom of the soaking drum mainly for the purpose of preventing the coking of line 7. Release valve 15 allows the maintenance of a high pressure on coil 4, drum 6 and separator 8. It will be understood that there is considerable pressure drop in the elongated coil 4 due to the passage of the oil therethrough at a high velocity but the pressure in drum 6 and separator 8 will be substantially the same since the pressure drop in the short line 7 is comparatively small. The preheated fresh feed is preferably introduced at the top plate of separator 8 which is provided with discs and doughnuts or equivalent separating and fractionating means. The introduced fresh feed cools the hot cracked effluent and checks thereby the further cracking, at the same time it is vaporized so that it leaves the separator in admixture with the cracked vapors through vapor line 16.

The liquid level control 17 connected with the release valve 18 and the bottoms line 19 allows the maintenance of a certain low liquid level in the separator and the removal of the unvaporized bottoms therefrom. The bottoms consists of tarry matter from the cracking and from the fresh feed in case an unclean charging stock is used as fresh feed. The vapors leaving through line 16 will be substantially free of any heavy tarry matter and are subjected to partial condensation and fractionation in heat exchangers 3, 11 and fractionating tower 20. The latter is provided with fractionating means such as bell cap plates and a heat exchange coil 10 at the top of the tower. The liquid which condenses in the tower 20 is collected in pan 21 from which it flows through line 22 into the accumulator 1. Similarly the condensed oil from heat exchangers 3 and 11 flows through 23 into the accumulator 1 to provide a clean charging stock for the cracking coil. There is connected with the lower end of the fractionating tower 20 a low pressure separator 24 into which the bottoms leaving the high pressure separator 8 through line 19 are discharged. Here the lower boiling constituents contained in the high pressure separator bottoms evaporate due to the release of the pressure and pass through center opening of pan 21 into the fractionating tower. Unvaporized tar is removed through line 25 and tar cooler 26 to a storage tank (not shown). The uncondensed oil vapors leave the top of the fractionating tower 20 through vapor line 27, are condensed in final condenser 28 and are obtained as naphtha after the separation and removal of the permanent gases through line 29. Due to the stability of the naphtha obtained in my process the sulfuric acid treatment may be eliminated and the stock may be finished by a clay treatment in a clay treating apparatus diagrammatically shown at 30 whereby a treated naphtha is obtained.

The operating conditions may be varied within a considerable range. The pressure main-

tained on the soaking drum and the high pressure separator is preferably higher than about 100 lbs. per square inch and is usually around 1,000 lbs. per square inch although pressures higher than that may also be employed. The 5 temperature to which the oil is heated in coil 4 may also vary within a broad range. It is usually higher than 800° F. and is preferably between 900° and 1000° F.

The following example will illustrate my invention.

A 31° A. P. I. West Texas gas oil was cracked according to the present invention, using a mixed feed rate to the cracking coil of 25,000 gallons 15 per hour of which 50% was fresh feed. The conditions of the cracking were the following:

	°F.
Coil outlet temperature	950
Soaking drum temperature	900
High pressure separator temperature	825
Coil inlet temperature	775

The pressures were the following:

	Lbs. per sq. inch	25
Hot feed pump	1,000	25
Soaker	750	25
High pressure separator	750	25
Bubble tower	100	25
Low pressure separator	100	30

The following yields were obtained:

	Percent
Distillate of 400° F. end point by volume	54.6
Fuel oil of 9° A. P. I. gravity by volume	31.6
Gas by weight	15.4

Various changes and modifications may be introduced without departing from the spirit of my invention. The same is therefore not to be limited by any particular details given merely as 40 illustrations but only by the appended claim in which it is my intention to claim all novelty inherent in the process:

What I claim is:

The process of cracking oil which comprises 45 heating a relatively clean distillate charging stock under high pressure to a cracking temperature in an elongated narrow heating zone and discharging the same to an enlarged digesting zone to effect the required amount of cracking, passing substantially all of the cracked effluent to an enlarged high pressure separating zone, maintaining substantially the same high pressure in the digesting and separating zones, introducing fresh feed oil below cracking temperature to the process, passing a part thereof into said digesting zone in proximity to the point of withdrawal of the heated oil therefrom, passing another part of said fresh feed oil into the separating zone, contacting said last mentioned part of said fresh feed oil with cracked effluent from the digesting zone to effect vaporization of the fresh oil at cracking temperature therein, removing oil vapor from the separating zone and fractionating the same under lower pressure than that in the separating zone to obtain the said relatively clean distillate charging stock and naphtha, returning clean distillate charging stock thus obtained to said heating zone as charge oil therefor, separately removing unvaporized bottoms from the separating zone and eliminating said bottoms from the system without subjecting them to thermal conversion.

HAROLD SYDNOR.
